UNITED STATES PATENT OFFICE.

EDWARD L. SILL, OF BLOOMINGTON, ILLINOIS.

HORSE-COLLAR.

No. 893,024.

Specification of Letters Patent.

Patented July 14, 1908.

Application filed July 24, 1907. Serial No. 385,367.

To all whom it may concern:

Be it known that I, EDWARD L. SILL, a citizen of the United States, residing at Bloomington, in the county of McLean and 5 State of Illinois, have invented a new and useful Horse-Collar, of which the following is a specification.

This invention relates generally to horse collars, and more particularly to that class 10 employing pneumatic cushioning elements.

The object of the invention is to improve the manner of combining the air cushion or tube with the collar sections, to simplify and cheapen the construction of the collar as a 15 whole, and to provide a novel form of fastener for holding the two sections of the collars assembled at the throat.

With the above and other objects in view, as will appear as the nature of the invention 20 is better understood, the same consists in the novel construction and combination of parts of a horse collar as will be hereinafter fully described and claimed.

In the accompanying drawings forming a 25 part of this specification and in which like characters of reference indicate corresponding parts, Figure 1 is a view in elevation of a horse collar constructed in accordance with the present invention, portions thereof being 30 broken away for purposes of clearness of illustration. Fig. 2 is a perspective detail view of the upper portion of the collar. Fig. 3 is a fragmentary detail view displaying one form of hame holder. Fig. 4 is a similar 35 view of another form of hame holder. Fig. 5 is a transverse sectional view on an enlarged scale through the throat portion of the collar exhibiting one form of locking means for holding the collar sections assembled. Fig. 40 6 is a view similar to Fig. 5, of a modified form of locking mechanism.

The collar, as usual, is constructed of two 45 sections, 1 and 2, which are made preferably of sheet metal stamped or otherwise shaped to the appropriate form, the upper or neck portions of the sections being connected by a curved bridge-plate 3 which is pivotally connected at 4 to the said sections. The lower or throat portion of each collar section 50 has secured within it a filler block 5 and 6, respectively, the filler block 5 being provided with two slightly tapered outwardly-projecting bolts 7, each of which is formed in its upper face with a recess 8 that is adapted to be 55 engaged by a latch 9 carried by the block 6. This latch comprises a head that is orificed

for the reception of the bolts, a shank 10 that projects through an opening provided in the block for the purpose, and a head 11 that is designed normally to lie flush with the outer 60 surface of the section 1, a spring 12 interposed between the inner wall of the socket 13 in the block 6, and the head 11 serving normally to retain the latch in engagement with the bolts, as clearly shown in Fig. 5. To release the collar sections in order to permit them to be spread apart for removing or positioning the collar, it will only be necessary to press the head 11 inward, whereupon the latch will be moved out of engagement with 65 the bolts and the collar sections will then be free to be moved to the position shown in Fig. 2. To effect the locking together of the sections it will only be necessary to bring them together and exert sufficient inward 70 pressure to overcome the resistance of the spring 12.

Each of the sections 1 and 2 is provided with inward turned flanges 14 that are adapted to be engaged by flaps or keepers 15 carried by a leather sheath or shield 16, the co-action between the flaps and flanges being such as to cause the sheath to be retained in position, but at the same time to permit of its ready removal when desired. As shown 80 in Fig. 1, the upper ends of the sheath overlap at the neck portion of the collar at 17, thereby to present a smooth surface to the animal's neck.

Arranged within the sections 1 and 2 and 85 the sheath is a canvas sack or holder 18 in which is disposed the pneumatic tube 19, the tube and the sack being shaped to conform practically to the contour of the collar sections. One end of the tube 19 is provided 90 with a valve 20 that projects through an orifice in the filler block 5 and carries a head or cap 21 by which it is closed. This valve may be such as is usually employed on pneumatic tires for preventing the escape of air, 100 and as this construction is well known detailed illustration thereof is deemed unnecessary. When the tube is to be filled it will only be necessary to release the latch 9, separate the collar section, remove the cap 21 105 and inflate the tube 19 with an ordinary bicycle pump.

In the form of the invention shown in Fig. 1, each of the sections 1 and 2 is provided with a tug hook 22 of the usual or any preferred character, and with this arrangement 110 hames will not be employed in connection

- with the collar, but should it be desired to adapt the collar for use with hames, in addition to the tug hooks, a metallic guttered hame holder 23 will be riveted or otherwise secured to each of the sections adjacent to its inner edge, and in these holders the hames will be seated. As shown in Fig. 3 the holders are continuous and will extend from the lower portion of each of the sections upward as far as may be necessary. Instead of employing continuous structures as shown in Fig. 1, the hame holders may be made in sections 24, as shown in Fig. 4, and be riveted or otherwise secured to the sections 1 and 2.
- 15 In assembling the different parts of the collar, the tube is first placed in the canvas bag and is then positioned in the sections 1 and 2, after which the sheath is assembled with the sections. The cap 21 of the valve 19 is removed and the tube is then inflated and as it expands it will press against the sheath and force it outward, whereby a yielding surface will always be presented to the animal's neck wearing the collar.
- 20 25 The improvements herein defined are sim-

ple in character, will be found thoroughly efficient and practical in use and may be readily applied to horse collars without requiring any expensive machinery for the purpose.

What is claimed is:—

30 A horse collar embodying two pivotally connected sections, a filler block carried by the lower or throat portion of each section, one of the blocks being provided with a bolt and the other with a socket to receive the 35 bolt and means for locking the bolt therein, a sheath carried by the sections, a pneumatic cushioning element held by the sheath, a valve carried by the cushioning element and extending through one of the filler blocks, and a cap carried by the projecting end of the valve.

35 In testimony that I claim the foregoing as my own, I have hereto affixed my signature in the presence of two witnesses.

EDWARD L. SILL.
